(57) **CLAIM**

The ornamental design for a robot, as shown and described.

DESCRIPTION

FIG. 1 is an angled view of a robot embodying an aspect of the design;

FIG. 2 is a top view of the robot of FIG. 1;

FIG. 3 is a front view of the robot of FIG. 1;

FIG. 4 is a back view of the robot of FIG. 1;

FIG. 5 is a left view of the robot of FIG. 1;

FIG. 6 is a right view of the robot of FIG. 1; and,

FIG. 7 is a bottom view of the robot of FIG. 1.

The subject matter in broken lines, showing environment or structure, is disclaimed and is provided for illustrative purposes only and forms no part of the claimed design.

1 Claim, 7 Drawing Sheets(56)
